UNITED STATES PATENT OFFICE.

BLONVILLE M. FITHIAN, OF BAXTER SPRINGS, KANSAS.

JOURNAL-BEARING-SHIFTING MECHANISM.

Application filed March 6, 1925. Serial No. 13,532.

To all whom it may concern:

Be it known that I, BLONVILLE M. FITHIAN, a citizen of the United States, residing at Baxter Springs, in the county of Cherokee and State of Kansas, have invented certain new and useful Improvements in Journal-Bearing-Shifting Mechanisms, of which the following is a specification.

This invention relates to mechanism especially adapted to be used for shifting and holding the journal bearing of a well drilling rig, and it consists in the novel features herein described and claimed.

An object of the invention is to provide a shifting and holding mechanism of the character stated, which is simple and durable, and which will positively and efficiently retain the teeth of planetary gear wheels in proper mesh with each other, and wherein by one wheel may be moved with relation to the other to compensate for and take up any wear which may occur upon the teeth of either wheel.

With the above object in view, the mechanism includes a frame which is disposed transversely of the shaft upon which one of the wheels is mounted, there being a bearing slidably mounted in the frame and in which the said shaft is journaled. A wedge shaped block is mounted for movement in the frame, and is adapted to slide along an inclined surface provided within the frame. One side edge of the block bears against the bearing. A lever is fulcrumed upon the frame, and is provided with an angularly disposed working end portion having a slot which receives a stud mounted upon the bearing. A rod is adjustably connected at one end portion with the intermediate portion of the power end of the lever and is connected at its other end with the said block, whereby when the lever is swung, the block is moved along the inclined surface in the frame, and the bearing is moved in the frame, so that one end of the bearing may at all times be positioned against one edge wall surface of the frame and one edge of the block may be retained against inclined surface of the frame and the adjacent edges of the bearing and block are held in close contact with each other.

In the accompanying drawing:

Figure 1 is a side elevation of the journal bearing shifting mechanism.

Figure 2 is an elevation thereof taken at right angles to Figure 1.

As illustrated in the accompanying drawing, the pinion of a well drilling rig is shown at 1, and the spur gear at 2. The teeth of the pinion and the spur gear are to be maintained in mesh with each other, regardless of any wear, which may take place in the teeth. The spur gear 2 is mounted upon a shaft 3, which is journaled in a bearing 4. The bearing 4 is slidably received in an opening 5 provided in a frame 6, which is disposed transversely of the shaft 3. The frame 6 is mounted upon and secured to a fixed support.

The opening 5 in the frame 6 is provided with an inclined side surface 7, and a wedge shaped block 8 is located in the said opening, and one edge bears against the surface 7 and the opposite edge of the block 8 bears against the adjacent edge of the bearing 4. A lever 9 is fulcrumed on the frame 6, and is provided with an angularly disposed working end portion 10, having a slot 11 leading in from the end thereof, and which receives a stud 12 mounted upon the bearing 4. A gear segment 13 is mounted adjacent the intermediate portion of the lever 9, and the latch mechanism 14 is carried by the lever and adapted to engage in the teeth of the segments 13, whereby the said lever 9 is held at an adjusted position. A rod 15 is adjustably secured by means of nuts 16 to the intermediate portion of the lever 9, and one end of the said rod 15 is pivotally connected with the wedge shaped block 8. A spring 17 is connected at one end with a positive means and at its other end with the lever 9, and is under tension with a tendency to hold the rod 15 in an elevated position with relation to the lever.

It will be apparent that as wear takes place upon the teeth of the pinion 1 or the spur gear 2, the lever 9 may be swung whereby the bearing 4 is moved along the opening 5 in the block 6, and the wedge shaped block 8 is moved along the inclined surface 7, so that the bearing 4 is positively held at an adjusted position and the teeth of the spur gear 2 are held properly in mesh with the teeth of the pinion 1.

Thus, means are provided for holding the teeth against movement diametrically of the spur gear and the pinion, and with relation to each other, and by eliminating such relative movement, the wear of the teeth is reduced to a minimum, and when such wear does occur, it may be compensated for by

shifting the lever, the bearing and the block, as hereinbefore described.

Having thus described my invention, what is claimed is:

- 5 A journal bearing shifting mechanism comprising a frame provided with an opening having a slanting wall, a bearing slidably mounted in the opening, a stud projecting from the bearing, a wedge-shaped block slidably mounted in the opening and having one edge engaging the slanting wall of the opening and an opposite
- 10

edge engaging the bearing, a lever fulcrumed upon the frame and having a recess to receive the stud carried by the bearing, a rod extending from the lever and engaged with the wedge-shaped block, and a spring engaged with the rod and the lever for holding the wedge-shaped block in engagement with the slanting wall of the opening.

In testimony whereof I affix my signature.

BLONVILLE M. FITHIAN.
